LE ROY W. HOYT, OF STAMFORD, CONNECTICUT.

INTERNAL-HEATED THROTTLE-VALVE FOR HYDROCARBON-ENGINES.

1,354,484.

Specification of Letters Patent.

Patented Oct. 5, 1920.

Application filed October 27, 1919. Serial No. 828,740.

To all whom it may concern:

Be it known that I, LE ROY W. HOYT, a citizen of the United States, residing at Stamford, county of Fairfield, State of Connecticut, have invented an Improvement in Internally-Heated Throttle-Valves for Hydrocarbon-Engines, of which the following is a specification.

This invention relates to hydrocarbon engines and has for its general objects to provide a structure which will greatly reduce fuel consumption, will insure vaporization of the lower grades of gasolene, will distribute the explosive mixture more uniformly and thoroughly and dry it out before it enter the engine cylinders, will permit quick starting and give greater flexibility to the engine, will practically eliminate carbonization and loading of the intake pipes, and will prevent the accumulation of moisture on the cylinder walls.

These results I accomplish by means of a novel throttle valve and a novel construction and combination of parts coöperating therewith. In brief I provide a novel structure which may be used in connection with any ordinary carburetor or with carburetors of special construction, important features of the present invention being that the ordinary butterfly throttle valve at the carburetor is eliminated, and that in lieu thereof I provide a sliding tubular throttle valve which is internally heated by utilization of part of the exhaust and which passes through the intake manifold and reciprocates in a Venturi chamber which is externally heated by a portion of the exhaust.

In the accompanying drawing forming part of this specification,

Figure 1 is a fragmentary elevation of so much of a hydrocarbon engine as is necessary to illustrate the application thereto of the present invention;

Fig. 2 a section on the line 2—2 in Fig. 1, looking in the direction of the arrows; and

Fig. 3 is an enlarged detail sectional view at right angles to the section line in Fig. 2, and also showing a slight modification in details of construction.

10 denotes the engine cylinders, 11 the intake manifold, 12 the exhaust manifold, 13 the Venturi chamber, 14 the heating jacket, 15 an exhaust connection, 16 the carburetor connection, and 17 the carburetor.

15 The inner wall of the Venturi chamber tapers inward and downward, the narrow-

est portion or neck thereof comprising a valve seat, as at 18. Below this valve seat the Venturi chamber opens into the carburetor connection. 19 denotes the tubular 60 throttle valve which is formed intermediate the ends of a throttle stem 20 and is tapered to correspond with the taper of the valve seat. The throttle stem passes through the intake manifold and through the carburetor 65 connections and has sliding bearings in a hub 21 above the intake manifold and in a hub 22 below the valve seat. The specific design of the throttle valve and valve seat is not of the essence of the invention. In Fig. 70 3 the valve and the Venturi chamber are shown as having corresponding relatively long straight tapers, while in Fig. 2 I have shown a slightly modified form in which a circumferential rib 23 on the valve 75 co-acts with a valve seat consisting of a corresponding rib at the lower end of the wall of the Venturi chamber.

As a means of operating the throttle valve I have shown a bell crank lever 24, one arm 80 of which is provided with a yoke 25 which engages lugs 26 at the lower end of the throttle stem, the other arm of said lever having attached thereto a connecting rod 27 which extends to a suitable operating member, not shown, as a pedal or a hand lever on the dash board or steering column of an automobile. The exhaust connection 15 leads from the exhaust manifold to a T-hub 28 from which pipes 29 and 30 extend. A 90 portion of the exhaust from the manifold passes to the T-hub and there divides, a portion passing through pipe 29, hub 21, and throttle stem 20, and out at the lower end thereof, the other portion passing through 95 pipe 30 to heating jacket 14 and out through exhaust connection 15. It is immaterial so far as the present invention is concerned what disposition is made of the exhaust from the valve tube and from connection 15. It 100 may pass directly to the open air or through connections leading to the main exhaust.

In starting the engine in cold weather, the throttle stem is primarily heated, as by pouring hot water through it, a funnel cup 105 31 being provided over T-hub 28 for convenience in pouring hot water through pipe 29 and into the throttle stem and valve. When an explosion takes place in the engine a part of the exhaust will pass through the 110 throttle stem and valve and a part of it will pass through the heating jacket, so that the

explosive mixture in the Venturi chamber and the intake manifold is heated both by the internally heated throttle valve and by the externally heated walls of the Venturi chamber. The manner of controlling the passage of explosive mixture from the carburetor to the Venturi chamber is practically the same as where an ordinary butterfly throttle valve is used. The present invention, however, provides an internally heated sliding throttle valve and in co-operation therewith a valve seat and Venturi chamber externally heated by the utilization of a portion of the exhaust. I am thus enabled to heat and dry the explosive mixture in the Venturi chamber just before it enters the intake manifold and thereby greatly improve the operation of the engine by giving it greater flexibility and with a reduced consumption of gasolene, owing to the more perfect vaporization of the gasolene, the heating, drying and uniform distribution of the mixture, and the practical elimination of carbonization.

Having thus described my invention, I claim:

1. In a hydrocarbon engine, a reciprocating throttle valve in combination with means for internally heating the same.
2. In a hydrocarbon engine, a reciprocating, tubular throttle valve in combination with means for internally heating the same.
3. The combination with a valve seat and a sliding throttle valve, of means for heating said valve seat and for internally heating said throttle valve.
4. The combination with a tapering valve seat, and a jacket and exhaust connections for heating the same, of a sliding tubular throttle valve and exhaust connections for internally heating said valve.
5. The combination with a tapering valve seat, and a jacket and exhaust connections for heating the same, of a correspondingly tapered throttle valve, a reciprocating tubu-

lar throttle stem by which said valve is carried, and exhaust connections for said throttle stem.

6. In combination an intake manifold, a tapering Venturi chamber opening into the manifold, a carburetor connection opening into the chamber, a valve seat at the neck of the chamber, a co-operating throttle valve, and a sliding throttle stem by which the valve is carried and which passes through the manifold, chamber and carburetor connection.

7. In combination an intake manifold, a tapering Venturi chamber opening into the manifold, a carburetor connection, opening into the chamber, a valve seat at the neck of the chamber, a heating jacket surrounding the Venturi chamber, a co-operating throttle valve, a sliding throttle stem by which the valve is carried, and exhaust connections to the heating jacket and to the throttle stem.

8. In a hydrocarbon engine the combination with an externally heated Venturi chamber having a valve seat, of an internally heated sliding throttle valve.

9. In a hydrocarbon engine the combination with a Venturi chamber having a valve seat and a heating jacket surrounding said chamber, of a sliding tubular throttle valve in said chamber and exhaust connections to the heating chamber and valve.

10. In a hydrocarbon engine the combination with an intake manifold, a Venturi chamber having a valve seat, a carburetor connection, and a heating jacket surrounding the chamber, of a sliding tubular throttle stem passing through the manifold, chamber and carburetor connection, a throttle valve carried by said stem and co-operating with the seat, and exhaust connections to the heating jacket and the throttle stem.

In testimony whereof I affix my signature.

LE ROY W. HOYT.
